REED FOR WIND INSTRUMENTS

Anthony Montenare, Reading, Pa.

Application December 23, 1949, Serial No. 134,697

10 Claims. (Cl. 84—375)

1

The invention herein described and claimed relates to wind operated musical instruments and more particularly to an improvement in reeds for such musical instruments. This invention is an improvement over those shown and claimed in my prior issued United States Patents Numbers 1,985,102, granted December 18, 1934, and 2,274,375, granted February 24, 1942.

Among the objects of the present invention is the provision of a reed block having a wide tongue; to improve the tonal qualities of the reed by providing a reed block with beveled sides, or even sides which are concave in cross-section; to further improve the reed tonal qualities by providing reed block sides which are slanted longitudinally toward the free end of the tongue supported by the reed block; to amplify and sweeten the tone from the reed by providing a special construction of reed block; to provide a valve construction for each reed block which eliminates the old type of side valve and gives longer life to the valve; to provide for maximum depth in the reed block for movement of the reed; to provide a construction wherein the tongue may be at least partially ground for tuning while in the reed block, and on both sides thereof to provide in one of its forms a two-part reed block having matching grooves, the pair of matching grooves on each side of the tongue forming in effect horns to provide tongue ends of special different configurations, i. e. pointed or square to give the desired tonal qualities; to provide a tongue with a weight of such weight or size to give it proper balance, and to provide a reed block that will be cheap to manufacture in large quantities.

Other objects will be apparent from an inspection of the drawings and of the following specification.

In the drawings:

Figure 1 is a vertical sectional view taken through the longitudinal central portion of a series of reed blocks, and showing a cell block in plan on an enlarged scale.

Figure 2 is a correspondingly cross sectional view of the cell block shown in Figure 1.

Figure 3 is a vertical sectional view taken longitudinally of the reed only.

Figure 4 is a transverse sectional view of the reed shown in Figure 3 on the line 4—4 thereof.

Figure 5 is a plan view of a modified form of reed half.

Figure 6 is a vertical sectional view of a second modification of the reed, taken on the line 6—6 of Figure 7.

2

Figure 7 is a vertical sectional view of the reed shown in Figure 6 and taken on the line 7—7 thereof.

Figure 8 is a plan view of a third modification of a reed block half, and

Figure 9 is a plan view of the opposite side of the reed half shown in Figure 8.

The principal use of the several forms of the reed of this invention pertains to use as parts of an accordion, such as shown in Figure 10 of my Patent 2,274,375. It will be understood that the devices of this invention may be used as parts of other wind instruments including mouth organs, hand organs, reed organs of the type employed in churches and other places, horns of the types entitled "wood winds" and "brasses," or any instruments which employ a vibrating tongue whose vibration is controlled by wind. As the reeds of this invention are self-contained, they may readily be substituted for the reeds of existing instruments of the types noted above, although an accordion will be referred to for purposes of convenience herein.

A suitable support for the reeds, herein shown as an accordion cell block 2, having transverse central partitions 4, provide a plurality of pairs of sound chambers 6 having an open side 8 to which the reeds or reed blocks 10 are semi-permanently attached by a suitable attaching substance, such as bees-wax, glue, natural resin or some forms of artificial resins 12.

The cell block is provided with openings 14 leading into the sound chambers 6, and may also be provided with ledges 16 for positioning and supporting the rows of reed blocks 10.

Each reed block comprises a pair of substantially identical sections 18 and 20 and these are held together at their opposite ends by the fastening means shown herein as headed rivets 22, 24 as shown in Figure 3.

The single tongue 26 of each reed has a fixed end 28 and a free end 30. The fixed end is clamped between block 32 and 34, and the tongue and blocks, which latter may each be integral with a reed section, are held from movement by rivet 24. The free end of the tongue is provided with a weight 32 of special construction whereby equal portions of the weight are on opposite sides of the tongue, and this is an important feature of the present invention. The particular shape of the weight is unimportant and it may assume the form of a rivet as shown, or of a nut on each side of the tongue, or any other form or configuration.

Beyond the free end of the tongue are trans-

verse walls 34, 36 that provide an additional chamber 38 and extending centrally of the chamber and held in position by rivet 22 is a flap valve 40. This is preferably of flexible material such as rubber or artificial rubber. The flap valve extends in the same plane as the tongue 26.

The reed block sections 18, 20 are provided with apertures 42, 44 respectively.

As seen particularly in Figure 4, the sides of each reed block are provided with pairs of sloping concave sides 46, 48, the oppositely facing side 46, 48 forming a horn shaped passage 50 on each side of the tongue, and these passages are horn shaped because like the longitudinal straight passage extending forwardly from the mouth piece of a bugle, the passages 50 become progressively larger in cross section from the end of the reed block adjacent the fixed end of the tongue towards the free end thereof. These passages 50, including their shape and their placement with relation to tongue 26, are important features which distinguish the present invention from the prior art devices.

The sides of the passages are closed by a removable covering 52 that has portions 54 and 56 respectively which preferably cover the exposed open top of one of the sections and across both ends of the sections.

Figure 5 is a modification of the embodiment shown in Figures 1 to 4. In Figure 5 which only shows one of the reed sections 54, it will be understood that the other reed section composing the pair of reed sections similar to that shown in Figure 4 will be the same as the section 54. The other block section is the same as the block section shown except, of course, only one tongue 56 would be used for the pair of reed block sections. This tongue is provided with a fixed end 58 and a free end 60. The aperture 62 corresponds to either of the apertures 42 or 44 of the structure shown in Figure 3. The two halves, only one of which is shown, are riveted to each other through the holes 64 and 66 in the same manner as will be noted by reference to Figure 3.

The principal difference of the reed block when formed, of a pair of reed sections such as shown in Figure 5, is that one or preferably both reed sections are provided with slanting sides 68 and 70, which sides are preferably plain surfaces. It will also be noted that each end 72 of these inclined sides which is adjacent the fixed end of the tongue 56 is wider than the forward ends.

For example, by referring to slanting side 68, it will be noted that the edges 74 and 76 converge toward each other and that the end 72 which is adjacent to the free end of the tongue is defined by a line which is of less distance than the line 80 which is adjacent the fixed end of the tongue. In order to provide this surface of the slanting side 68 which is the same as the surface of the slanting side 70, either side edge 74 or 76 may converge, but it is preferable that the upper side edge 76 converge rather than the lower edge 74, but it is within the scope of this invention to provide a slanting side having both of its side edges 74 and 76 converging toward each other.

It is also within the scope of this invention, although not disclosed, to provide, instead of the sloping concave sides shown at 48 in Figure 4 or the plain sides shown in 70 and 72 of Figure 5 to provide these surfaces as convex surfaces. Referring again to Figures 1 to 4, the tongue 26 vibrates in a space 100 formed by the space in the reed sections both above and below the tongue

shown in Figure 4. Additionally, there is a space 102 in the reed section shown in Figure 5 in which the tongue 56 may vibrate, and in a corresponding space shown in the complementary reed section which is attached to the reed section shown in Figure 5.

In Figures 6 and 7, 82 indicates a reed block consisting of complementary reed sections 84 and 86, these reed sections being attached to each other by the rivets 88 and 90. The tongue 92 has ends fixed and attached by means of the rivet 90 and its free end is provided with a weight 94 which provides an equal amount of weight on each side of the tongue. The additional chamber 96 is similar to the chamber 38 except that it is substantially cylindrical in cross section as seen in Fig. 6. In this chamber there is a free reed or member 98 which is cylindrical in cross section as seen in Figures 6 and 7, and the chamber is provided with apertures 104 and 106 corresponding to apertures 42 and 44 in Figure 3. The free reed corresponds to the flap valve 40 shown in Figure 3 inasmuch as it is adapted to close either aperture 104 or 106 according to the movement of wind within the reed.

Another essential difference and important feature of invention disclosed in Figures 6 and 7 are the substantially semi-cylindrical grooves 108 and 110. These grooves are narrower at the ends 112 and radius increases gradually toward their opposite ends 114, that is, the ends adjacent to the free end of the tongue. These pairs of grooves when the sections are attached to each other as shown in Figures 6 and 7 form passageways the radius of which becomes progressively larger and to this extent they resemble the passageway in a bugle adjacent to the mouthpiece thereon which also becomes greater in radius as it progresses toward the first turn of the bugle. It will be noted that the inner ends 116 and 118 gradually separate from each other as seen in Figure 6. This construction of grooves and centrally positioned tongue, as well as the additional chamber all add materially to the tonal qualities of the wind instrument of which they form a part.

Referring to Figure 9, the reed block is indicated by the numeral 120 and this reed block consists of a pair of sections one of which 122 is shown in Figure 8. The sections are held to each other by rivets 124 and 126 and the space for the tongue 128 to vibrate in is indicated by 130.

The additional space is indicated by the numeral 132 and leading into this space are a pair of openings 134 and 136, which openings only extend through one of the sections, the opposite ends being closed. Clamped by means of the rivets 124 and 126 are a pair of flap valves 138 and 140 which extend between the sections in the same way that the flap valve 40 extends between the sections as shown in Figure 3.

It will be noted that the tongue 128 is provided with a weight 142 on its free end, and this free end is provided with a point 144 having slanting sides 146 and 148. Although a pointed tongue is shown it should be appreciated that this tongue may be rounded to form a half circle, or the free end of the tongue may be provided with right angled corners as shown in Figures 1 and 5. It has been determined that the tonal qualities vary considerably according to the shape of the end of the tongue. A tongue having an end of the shape shown in Figure 8 may depend upon the instrument used and other factors (such as the shape and size of the grooves) as, for instance,

shown at 108 and 110 in Figure 7 or the sides 70 and 72 in Figure 5 or the concave side shown in Figure 4. The shape of the end of the tongue may also depend upon the shape and size of the additional chambers such as shown at 38 in Figure 3 or 96 of Figures 6 and 7.

Referring again to Figures 6 and 7, it will be noted that the reed block has a cover 146 similar to the cover 56 having ends 148 and 150. However, there is a raised portion on this cover indicated at 152 for the purpose of fitting in the air cells 6 of the cell block. A special advantage, in addition to that of improving the tonal qualities of the reeds, is to provide cell blocks composed of complementary sections of fairly rugged material, because, as will be noted by reference to Figures 3, 4, 5, 6 and 8, such reed block sections may be easily produced by a comparatively simple molding operation. In other words, the section shown in Figure 5, for instance, without the tongue may be readily molded by pouring molten metal in a mold which will readily produce the reed block sections. A large number of molds may be filled one after the other, thus producing a large number of reed block sections and such reed block sections may be in conformity with the structure shown in other figures, such as Figure 4 or 6 showing other forms of the invention. After the sections have been molded, the tongues are inserted in the proper place and the sections are connected together by riveting, the flap valve 40 is inserted or the free reed 98 which comprises a valve is inserted, the covers shown in the several figures are then applied and the reed block is ready for use. If desired, the free reed 98 may be inserted after the sections have been riveted to each other before the cover has been applied.

In the present invention the tongues may be filed down on both sides without taking the same out of the reed block and this is a great advantage as it saves much time and effort in tuning the reeds, as in the present invention it is only necessary to remove the cover, which is usually made of paper or some easily removable material before filing either or both sides of the tongue. The shape of the reed block enables a particularly wide reed to be used in the present construction and this is an insurance against frequent tuning. However, when the reed does need tuning, the tongue may be readily filed down by using a flat file or a "rat tail" file, by merely putting a support under the tongue so as to hold it in proper position for the filing operation. Although several forms of the invention have been shown, it is to be understood that the reeds shown are not necessarily limited thereto as they may be applied to any other wind instruments which rely on reeds for the musical sounds. It is to be further understood that the drawings and description of the present invention are for illustrative purposes and not to be construed in limiting the invention to the constructions shown, as I desire to be limited only to the extent set forth by the appended claims.

I claim:

1. A reed for wind instruments comprising a reed block, a tongue having ends, one of which ends being fixed in said reed block and the other end being free, said tongue extending substantially medially along the longitudinal axis of said reed block and said reed block having sloping sides on both sides of said tongue, said sides forming passages varying in width from the fixed to the free end of the tongue.

2. A reed for wind instruments comprising a reed block, a tongue having ends, one of which ends being fixed in said reed block and the other end being free, said tongue extending substantially medially along the longitudinal axis of said reed block and said reed block having sloping concave sides on both sides of said tongue, said sloping concave sides forming horn shaped passages varying in size from the fixed to the free end of said tongue.

3. A reed for wind instruments comprising a reed block, a tongue having ends, one of which ends being fixed in said reed block and the other end being free, said tongue extending substantially medially along the longitudinal axis of said reed block and said reed block having sloping plain sides on both sides of said tongue, said sloping plain sides forming passages extending substantially the length of said tongue and progressively increasing in diameter from one end of the tongue to its other end.

4. A reed for wind instruments comprising a reed block, a tongue having ends, one of said ends being fixed in said reed block and the other end being free, said tongue extending substantially medially along the longitudinal axis of said reed block, an additional chamber in said block located adjacent to and above the free end of said tongue, said additional chamber having angled sides and a flap valve mounted in said chamber.

5. A reed for wind instruments comprising a reed block composed of a plurality of sections, a tongue having ends, one of said ends being fixed in said reed block and the other end being free, said tongue extending substantially medially along the longitudinal axis of said reed block, an additional chamber in said block located adjacent to and above the free end of said tongue, said additional chamber having angled sides and a flap valve mounted in said chamber having an end fixed within said chamber.

6. A reed for wind instruments comprising a reed block, a tongue having ends, one of said ends being fixed in said reed block and the other end being free, said tongue extending substantially medially along the longitudinal axis of said reed block, an additional chamber in said block above and adjacent the free end of said tongue and a free floating valve member in said chamber.

7. A reed for wind instruments comprising a reed block, a tongue having ends, one of said ends being fixed in said reed block and the other end being free, said tongue extending substantially medially along the longitudinal axis of said reed block, an additional chamber in said block above and adjacent the free end of said tongue, a pair of openings in said chamber and a pair of flap valves each having an end fixed in said chamber adapted to close one of said openings.

8. A reed for wind instruments comprising a reed block, a tongue having ends, one of said ends being fixed in said reed block and the other end being free, said tongue extending substantially medially along the longitudinal axis of said reed block, an additional chamber in said block located adjacent to and above the free end of said tongue, said chamber having a valve member mounted therein, said block having sloping sides forming passages varying in width from the fixed to the free end of the tongue.

9. A reed for wind instruments comprising a reed block, a tongue having ends, one of said ends being fixed in said reed block and the other end being free, said tongue extending substan-

tially medially along the longitudinal axis of said reed block, an additional chamber in said block located adjacent to and above the free end of said tongue, said chamber having a valve member mounted therein, said block having sloping concave sides on both sides of said tongue, said sloping concave sides forming horn shaped passages varying in size from the fixed to the free end of said tongue.

10. A reed for wind instruments comprising a reed block, a tongue having ends, one of said ends being fixed in said reed block and the other end being free, said tongue extending substantially medially along the longitudinal axis of said reed block, an additional chamber in said block above and adjacent the free end of said tongue and a free floating valve member in said chamber, said

5 block having a groove on each side of said tongue, the radius of each groove varying in size from the fixed to the free end of said tongue.
